Primary Examiner—Philip S. Hyder*Assistant Examiner*—Cynthia Underwood(74) *Attorney, Agent, or Firm*—Foley & Lardner LLP**CLAIM**

We claim the ornamental design for a double walled metallic bowl, as shown and described.

DESCRIPTION

FIG. 1 is a top perspective view of a double walled metallic bowl according to my new design.

FIG. 2 is a front elevational view thereof, the rear elevational view, left end elevational view and right end elevational view being the same as the front elevational view shown;

FIG. 3 is a top plan view thereof;

FIG. 4 is bottom plan view thereof; and,

FIG. 5 is a sectional view thereof taken along line 5—5 of FIG. 3.
